UNITED STATES PATENT OFFICE

2,508,544

ELECTROACOUSTIC TRANSDUCER DEVICE

Harry B. Shaper, Astoria, N. Y., assignor to The
Brush Development Company, Cleveland, Ohio,
a corporation of Ohio

Application March 1, 1947, Serial No. 731,786

3 Claims. (Cl. 179—1)

1

My invention pertains to a transducer having a variable frequency response pattern.

An object of my invention is to provide a transducer whose frequency response pattern can easily be changed.

A further object of my invention is to provide a transducer having a directional pattern in the form of a beam, the breadth or spread of which may easily be controlled.

Other objects and a fuller understanding of my invention may be had by referring to the following description, claims, and drawings, wherein:

Figure 1 is a sectional side view of a transducer embodying my invention.

Figure 2 is a plan view, on an enlarged scale, of a portion of the transducer shown in Figure 1.

Figure 3 is a schematic view, on an enlarged scale, illustrating the electrical connections in the transducer shown in Figures 1 and 2, and

Figures 4 and 5 are frequency response diagrams showing some of the patterns obtainable with the transducer shown in Figure 1.

With reference to the drawings, my transducer comprises a parabolic reflector 10 formed of metal or other material having satisfactory vibrational wave-reflecting properties. The narrow portion of the reflector 10 is turned inwardly toward its focal point 13 until it lies in a plane substantially perpendicular to the axis of the reflector, and a large circular opening 14 is provided in this planar portion.

A transducer assembly, indicated generally by the reference character 15, is connected to the reflector 10 by means of a plurality of screws 16 with the transducer diaphragm 17 substantially closing the opening 14 in the narrow end of the reflector 10, and with the center of the diaphragm located at the focal point 13 of the parabolic reflector.

The transducer assembly 15 is comprised of a massive base 20, preferably made of Bakelite or some other hard, stable, insulating material, having a cavity 18. A diaphragm 17 is secured to the base 20 by means of screws 19 and is so positioned that it closes the cavity 18 in the base 20.

A plurality of expander transducer means 21 are positioned within the cavity with their end faces secured in engagement with the base 20 and with the diaphragm 17. The transducers preferably are expander piezoelectric crystal elements so oriented that a direction of expansion and contraction is perpendicular to the plane of the diaphragm 17, although other transducer means such, for example, as the magnetostrictive type may be utilized. The transducer leads are

10 brought out through holes 22 in the base 20 and are connected to a number of solder lugs 23 secured to the back face of the base 20 by means of screws 24.

15 A cup-shaped housing 27, preferably formed of an insulating material such as Bakelite, and having a cable inlet opening to accommodate the cable 28 is provided. A grommet 29 is inserted in the cable opening and a cable clamp 30 is secured to the inside of the housing 27 to prevent the cable from pulling out of the housing. The cable is comprised of a number of wires, including a ground wire which may be the cable shield, and these wires are soldered to their respective solder lug 23. The housing 27 is then slipped over the base 20 and a plurality of screws 25 are put in place to secure them together.

20 Figure 2 is a plan view, on an enlarged scale, of the transducer assembly 15 with the diaphragm 17 partially broken away. The expander piezoelectric crystals are arranged in a plurality of "rings" B and C about a central group A, and the individual crystals which comprise each group preferably are connected in parallel, as is shown 25 in Figure 3. A constant voltage amplifier 30 is connected through a selector switch 31 in such a manner that any one of the crystal groups A, B or C can be energized by itself, or in combination with either of the other two groups, or in combination with both of the other two groups.

25 With only the crystal group A energized the directional pattern of the transducer and reflector will be as indicated by the pattern A in Figure 4, with only the ring B energized it will be as indicated by the pattern B, and with only the ring C energized it will be as indicated by the pattern C. The sharpest (or most directional) pattern is obtained with the use of the group A because they are located substantially at the focal point 13 of the parabolic reflector, and vibrational waves emanating from the focal point and spreading in all directions therefrom will strike the parabolic reflector 10 and be reflected in a beam substantially parallel to the axis of the reflector. Because the crystal rings B and C are located away from the focal point 13 their patterns will be broader than the pattern of the A group, as is shown by Figure 4. Accordingly, by connecting the crystal groups A, B, and C so that 30 any combination of one or more of them can be energized by the amplifier 30, directional patterns are easily obtainable which vary from the individual patterns shown in Figure 4 to the pattern shown in Figure 5 when all of the crystal groups 35 are simultaneously energized.

While I have described the operation of my invention with the amplifier 30 energizing the crystals, i. e., as a loudspeaker, it is to be understood that it operates just as well as a microphone device wherein the several crystal groups, either singly or together, generate voltages in accordance with a received pressure wave and control the amplifier 30 in accordance therewith.

While not essential, it may be desirable that the energy given out by the several groups of crystals (when operating as a speaker) should be equal. This may be achieved by making equal the total area of the end faces of the crystals in the several groups A, B and C, as is shown in Figures 2 and 3.

My invention is adapted for use in air or liquid, although the construction shown in Figure 1 is particularly useful in air. Suitable modifications may easily be incorporated to make the device useful under water.

Whether a device constructed in accordance with my invention is used in air or liquid, it has its sharpest directional characteristics at the higher frequencies, and in any event the length of the path from the focal point 13 to the parabolic reflector and the width of the mouth of the reflector should be about five times the length of the longest wave in the medium in which the device is operating.

While I have described my invention with a certain degree of particularity, it is to be understood that it has been by way of example and that changes can be made without departing from the spirit and scope of my invention.

I claim as my invention:

1. In a transducer, an open parabolic reflector of sound-waves having an axis of symmetry,

first expander electromechanical transducer means located substantially at the focal point of said parabolic reflector, second electromechanical transducer means comprising a plurality of individual transducers all connected in parallel located symmetrically around said first transducer means but away from the said focal point, said first and second transducer means facing the open end of said reflector and adapted to expand in a direction parallel to said axis, amplifier means, first and second electrical circuit means connected, respectively, to said first and second transducer means; and switch means for connecting said first and said second transducer means individually to said amplifier, and for connecting said first and said second transducer means simultaneously to said amplifier.

2. The invention set forth in claim 1, further characterized in this: that the area of the end face of said first transducer means is substantially equal to the area of the end face of said second transducer means.

3. A transducer as set forth in claim 1, further characterized by said amplifier means being a constant voltage amplifier.

HARRY B. SHAPER.
